UNITED STATES PATENT OFFICE.

CHARLES KOEHLER, OF PASSAIC, NEW JERSEY.

FABRIC-FRAME FOR EMBROIDERY-MACHINES.

1,072,623.

Specification of Letters Patent.

Patented Sept. 9, 1913.

Application filed December 11, 1912. Serial No. 736,100.

To all whom it may concern:

Be it known that I, CHARLES KOEHLER, a citizen of the Republic of Switzerland, residing at Passaic, in the county of Passaic 5 and State of New Jersey, have invented certain new and useful Improvements in Fabric-Frames for Embroidery-Machines, of which the following is a specification.

The object of this invention is to provide 10 a frame for holding the fabric or fabric pieces in embroidery machines which will be an improvement on such frames now used in that it will possess all of certain features of advantage of which at best only one or 15 some are possessed by any one type of such frames now used, to wit: that the improved frame will be at once light, simple and strong in construction, permit either large or small designs to be worked out in each 20 fabric held thereby, may be used to quite the same advantage in a shuttle machine as in a hand machine, and not only facilitate the application thereto and removal therefrom of the fabric pieces but hold them always 25 uniformly stretched as to the whole of the portion being worked upon.

In the accompanying drawing, Figure 1 is 30 a plan view of a fragment of the improved frame, showing two of the fabric holders partly in section; Fig. 2 is a vertical sectional view of the frame, showing a fabric holder in side elevation; Fig. 3 is a horizontal sectional view in a plane between the upper and lower strips of the frame; and, 35 Fig. 4 is a perspective view of one of the fabric holding clips.

a a' designates two parallel substantially sheet-like strips which, being parts of the improved frame, afford a convenient and 40 effective hold to clamps or the like whereby the frame is secured to the frame of the embroidery machine. These are arranged with their front faces nearly in the same place, as seen in Fig. 2. The upper strip has the 45 elongated apertures *c*, regularly spaced, and it is somewhat thicker and hence stiffer than the lower frame; it is thus well adapted as the part of the frame by which the latter is handled in transporting it to and from the 50 machine.

d designates the fabric holders, each being an endless or continuous member having a continuous peripheral groove *e*; they are preferably of oval shape, as shown. Each 55 fabric holder is secured to each strip *a a'* in some way calculated to produce a rigid joint

between them, as by placing the extremity of each holder against the front (broad) face of the strip and driving two screws *f* through the holder into the strip. The holders have 60 recesses *b* receiving the lower strip, the object of which is to reduce the thickness of the entire frame, thus affording room for the proper working of the horizontally moving needles in the embroidery machine, it being 65 noted that the holders themselves with the same purpose in view are made as thin as possible conditioned upon their having such thickness (or width of peripheral surface) as is needed to secure the proper gripping 70 action for the bands (to be described) which embrace them and hold the fabric pieces thereto.

The various holders are preferably constructed of aluminum; the strips *a a'* are 75 formed of steel. Thus constructed, the frame proper is a structure which, while strong and durable, may not only include as large a number of holders as could be required but is still light enough to be handled 80 with facility and convenience.

The fabric-pieces, designated *g*, are held 85 stretched over the holders by the endless constricting bands *h* or *i*. The bands *h* (one in Fig. 1) are designed for securing fabrics such being shown on the left-hand holder of coarser texture to the holders; each of 90 these consists of a continuous or endless spirally wound wire. The bands *i* are designed for securing in place fabrics of fine textures (one such being shown on the right-hand holder in Fig. 1) and each includes a piece 95 of non-extensible wire *ii* having its ends hooked to each other and an elastic rubber tube *ii'* forming a casing for the wire. In both cases the band is too small in diameter to be fitted around and into the groove of the holder without distention—in the form *h*, accomplished by longitudinal extension of the band and in the form *i*, by compression 100 of the elastic tube or casing *ii'*.

In fitting the fabric-pieces (for instance, handkerchiefs) in place each piece is individually secured by a clip *j*, such as that shown in Fig. 4, to the upper strip *a*. Then, 105 having if necessary, in the manner shown in Fig. 3, rolled up that part of the fabric which is not to be embroidered, the remainder of the piece is laid over the adjoining holder. Then, keeping the material smooth 110 throughout, the band is placed upon the material and then forced around the front edge

of the holder and gradually worked into completely received position in the groove of the holder. It will be found that this method of securing a fabric in position to be worked is of peculiar advantage not only in that it holds the material firmly and keeps it evenly distended while being embroidered, but in that it greatly facilitates and expedites the operation of applying the fabric-pieces to the frame. The removal of each band in order to release the fabric-piece held thereby is readily accomplished, preferably by beginning the removing operation at one side of the holder.

Having thus fully described my invention, what I claim as new and desire to secure by Letters Patent is:—

1. A fabric holding frame for an embroidery machine comprising parallel spaced substantially sheet-like strips, rigid flat open fabric holders arranged side by side and spaced from each other and each rigidly secured against corresponding broad faces of both strips, and a continuous constricting band embracing each holder, the fabric being adapted to be placed over each holder

and there held stretched over the same by thereupon fitting the corresponding band to the holder over and around the fabric, substantially as described.

2. A fabric holding frame for an embroidery machine comprising parallel spaced substantially sheet-like strips, rigid flat endless fabric holders arranged side by side and spaced from each other and each rigidly secured against corresponding broad faces of both strips, each holder being peripherally grooved, and a continuous constricting band embracing each holder and continuously occupying the groove thereof, the fabric being adapted to be placed over each holder and there held stretched over the same by thereupon fitting the corresponding band to the holder over and around the fabric, substantially as described.

In testimony whereof I affix my signature in presence of two witnesses.

CHARLES KOEHLER.
